UNITED STATES PATENT OFFICE.

EUGENE E. GOLLER, OF CHICAGO, ILLINOIS, ASSIGNOR TO UNIQUE MANUFACTURING COMPANY, OF CHICAGO, ILLINOIS, A CORPORATION OF ILLINOIS.

VAPORIZING NOZZLE.

Application filed June 23, 1926. Serial No. 118,123.

My invention relates to blow torches and the like and particularly to the nozzle which has the combined function of serving as a mixing chamber for the fuel and air, and the walls of which contain passages which are heated by the flame from the burner orifice so as to vaporize said fuel ready for combustion.

The object of my invention is to provide a vaporizing nozzle of simple and sturdy construction adapted to be used with fuel such as kerosene and other hydro-carbons requiring heat for vaporization.

A further object of my invention is to provide a vaporizing nozzle with a plurality of longitudinal passageways formed in the walls thereof, said passageways being all connected in series so as to form one continuous passageway through which the fuel is required to pass and which, when heated by the flame extending from the burner orifice, will be vaporized completely so that no liquid fuel will be delivered to the orifice.

Various experiments and tests in connection with vaporizing nozzles have revealed that in order to obtain perfect combustion of the fuel the same must be obstructed in its passage therethrough and in my improved device I have provided transverse ribs which, besides providing communication between the longitudinal passages, act as an obstruction to the fuel and when the same is directed against the same from the burner orifice, there is a tendency for the fuel to rebound and break up, becoming thereby better mixed with air, and capable of being entirely consumed which is not the case where the fuel is free to pass entirely through the nozzle without obstruction.

Many other advantages and objects of my invention will be apparent when considered in connection with the following description, reference being had to the accompanying drawings, in which:

Figure 1 is a longitudinal sectional view of my improved vaporizing nozzle showing the valve mechanism for controlling the burner orifice and the cover plate for confining the heat units and preventing wind from affecting the chilling of the vaporizer.

Fig. 2 is a like view taken on the line 2—2 of Fig. 1 and shows the connections between the vaporizing nozzle and the valve controlled burner orifice;

Fig. 3 is a cross sectional view taken on

the line 3—3 of Fig. 1 and looking in the direction of the arrows; and

Fig. 4 is a similar view taken on the line 4—4 of Fig. 1 and looking in the direction of the arrows thereon.

In each of the figures of the drawing like symbols indicate like parts.

Referring more particularly to the drawing, 6 represents my improved vaporizing nozzle which has the combined uses of acting as an obstruction to the fuel and serving as a mixing chamber in addition to its function as a vaporizer.

This nozzle is formed of a single casting preferably of brass or other suitable material and has a barrel or body portion 7 and a cone-shaped mouth 8 through which the flame is directed. The barrel portion is provided near the rear of the same with a downwardly projecting boss 9 terminating in a hexagonal or square shaped section 11, which is secured upon or otherwise attached to a reservoir (not shown) which contains the liquid fuel such as kerosene or other hydrocarbons.

In the nozzle which I have shown in the drawing there are four longitudinal ribs designated as 12, 13, 14 and 15, respectively, formed integral with the outer wall 16 of the same and the ribs 12 and 14 are connected by a transverse rib 17 which is located in the front of the said barrel portion and adjacent the cone-shaped mouth 8, while a transverse rib 18 is formed immediately behind the rib 17 and connects with the longitudinal ribs 13 and 15. At a position near the rear of the barrel portion is a rib 19 which extends between the longitudinal ribs 13 and 14 and is within the central chamber 21 extending through the said barrel portion and adapted to receive the fuel mixture through the opening 22 at the rear thereof. The ribs 12 and 14 are each drilled from the rear of the nozzle to provide the passage-ways 23 and 24 and these passage-ways communicate with a passage-way 26 drilled through the transverse rib 17. The rear ends of the passage-ways 23 and 24 are closed by stud bolts 27 and 28 secured into the same as shown in the drawing but other solder may be used if desired, and the bottom opening through which the passage-way 26 has been drilled into the rib 17 is closed by silver soldering or plugged as shown at 29. The ribs 13 and 15 are also

105 110

provided with drilled passages 31 and 32 and the inner ends of said passages communicate with a drilled passage 33 extending through the rib 18 and the rear end of the passage 31 is plugged or closed by a stud bolt 34 secured into the same. The bottom of the passage 33 is silver soldered as at 36 and the passage 32 communicates at its rear end with a pipe 37 which is threaded into the same as at 38 and the joint silver soldered as at 39. The rib 19 extending between the longitudinal ribs 13 and 14 is provided with a passage 40 which communicates with the longitudinal passages 24 and 31 and the outer end of this passage, which constitutes the drilled opening, is provided with a plug 45 for closing the same.

The outer end of the pipe 37 is threaded into the end of the arm 40 on the member 41 and silver soldered or plugged as at 42 and this arm is also provided with a passage-way 43, which is drilled into the same, and the outer end of the drilled passage-way closed, as at 44, with silver solder. At the extreme front end of the member 41 is the ejector nozzle 46 through which a needle 47 is adapted to project. The regulating valve is provided with an operating handle 48 at the rear end of the member 41 and said handle is attached to a screw 49 which has the valve face 51 for fitting into the seat 52 so that by turning the said handle the flow of fuel from the passage 43 to the orifice 46 may be permitted or interrupted by the valve 51 and the nozzle be kept clean by the movement of the needle 47 back and forth through the same. The member 41 is also provided with lugs 53 and 54 to which the end wall 56 of a shield 57 is attached by the screws 58 and this shield has outwardly flared portions 59 at the lower ends of the same and is provided with a hooked member 61 on the top thereof for supporting a soldering iron. The boss 9 is provided with a central passage 62 which communicates at its upper end with the longitudinal passage 23 in the rib 12 and constitutes the passage through which the fuel from the reservoir (not shown) is admitted under pressure to the vaporizing nozzle. The outer wall 16 of the barrel portion 7 of the vaporizing nozzle is provided with openings 63 between the longitudinal ribs for admitting air to the central chamber 21 for mixture with the fuel.

It will thus be seen that when the fuel is admitted from the reservoir (not shown) through the passage 62 in the boss 9 into the passage 23 in the rib 12, it takes a tortuous and continuous route through the passage 26 in the transverse rib 17, the passage 24 in the longitudinal rib 14, through the passage 40 in the cross rib 19, thence through the passage 31 in the longitudinal rib 13, the passage 33 in the transverse rib 18, the longitudinal passage 32 in the rib 15 and thence

through the pipe 37 into the passage 43 in the arm 40 of the member 41, where it is controlled by the valve 51 in its entrance to the ejector nozzle 46. Immediately beneath the boss 11 the reservoir is provided with a priming pan (not shown) which is used for heating the nozzle when the torch is first used.

It will be readily seen that the transverse ribs 17 and 18, extending across the central chamber 21 will retard the free flow of the mixture through the mouth 8 of the nozzle and these ribs will form a restriction against which the fuel will strike when it is ejected from the burner nozzle and it will rebound into the chamber 21 and become thoroughly mixed with air so that it will be completely burned therein.

It will be apparent that the nozzle may be readily constructed of a single casting with the passage-ways drilled as explained and the openings caused by the drill on the outer surface of the same can be plugged with silver solder as described and the longitudinal passage-ways plugged with the stud bolts 27, 28 and 34.

While I have shown the nozzle as having four longitudinal ribs and two transverse ribs extending across the central chamber 21, I do not limit myself to this or any other specific number nor do I limit myself to any of the details of construction herein shown which are capable of wide modification and variation without departing from the spirit of the invention. In order that I may reserve all these variations, modifications and mechanical equivalents, I claim all such structures as may fall within the spirit and scope of the appended claims:

I claim:

1. A vaporizing nozzle for blow torches and the like, which comprises a hollow casting, longitudinal tubular passages for liquid fuel in the walls thereof; transverse tubes connecting said passages, said tubes crossing at right-angles to each other and also being at right-angles with said tubular passages; an ejector nozzle for vaporized fuel in communication with said passages and located rearwardly of said transverse tubes and in line with the point at which said tubes cross so as to direct a stream of flame against said transverse tubes to heat them and vaporize the liquid fuel passing therethrough; a flame orifice in the end of said casting opposite to said ejector nozzle; and means, comprising a threaded opening communicating with said passages, for connecting said nozzle to a fuel supply.

2. A vaporizing nozzle for blow torches and the like, which comprises a hollow casting, four longitudinal tubular passages for liquid fuel in the walls thereof; two transverse tubes connecting said passages, said tubes crossing at right-angles to each other and also being at right-angles with said

- tubular passages; an ejector nozzle for vaporized fuel in communication with said passages and located rearwardly of said transverse tubes and in line with the point 5 at which said tubes cross so as to direct a stream of flame against said transverse tubes to heat them and vaporize the liquid fuel passing therethrough; a flame orifice in the end of said casting opposite to said ejector 10 nozzle; and means, comprising a threaded opening communicating with said passages, for connecting said nozzle to a fuel supply.
3. A vaporizing nozzle for blow torches and the like, which comprises a tubular 15 metallic member having longitudinal passages in the walls thereof; an ejector nozzle for vaporized fuel in communication with said passages and located at the rear of said metallic member; transverse tubes connecting 20 said longitudinal passages and crossing at right-angles to each other a substantial distance in front of and in line with said ejector nozzle; and means for connecting said passages with a supply of liquid fuel.
- 25 4. A vaporizing nozzle for blow torches and the like, which comprises a hollow metallic casting having passages for liquid fuel, said passages being located in the path of a flame resulting from the combustion of 30 vaporized liquid fuel passing through said passages; said passages consisting of tubes crossing each other at right-angles substan-

tially centrally within said casting; longitudinal passages in the walls of said casting and in communication with said first-mentioned passages; and means for connecting all of said passages to a supply of liquid fuel.

5. A vaporizing nozzle for blow torches and the like, which comprises a hollow metallic casting; four longitudinal passages in the walls thereof, a transverse tube extending from a passage in one side of said casting to a second corresponding passage at the side directly opposite thereof; a second transverse tube at right angles to the first-mentioned transverse tube extending from a third longitudinal passage to a fourth longitudinal passage at the side directly opposite thereof; an ejector nozzle in communication with the fourth longitudinal passage; a fuel supply pipe in communication with the first longitudinal passage; all of the aforementioned passages and tubes forming a single continuous passage 55 for liquid fuel from said fuel supply pipe to said ejector nozzle, said continuous passage passing at least twice at right-angles to the flame produced by burning the fuel ejected from said ejector nozzle.

In witness whereof, I have hereunto subscribed my name.

EUGENE E. GOLLER
